UNITED STATES PATENT OFFICE.

DANIEL MILLS, OF PHILADELPHIA, PENNSYLVANIA, ASSIGNOR TO THE STANDARD SEWING MACHINE COMPANY, OF CLEVELAND, OHIO, A CORPORATION OF OHIO.

BOBBIN-THREAD CONTROLLER FOR SEWING-MACHINES.

No. 927,993.

Specification of Letters Patent.

Patented July 13, 1909.

Application filed November 24, 1896. Serial No. 613,325.

To all whom it may concern:

Be it known that I, DANIEL MILLS, a citizen of the United States, residing in Philadelphia, State of Pennsylvania, have invented certain new and useful Improvements in Bobbin-Thread Controllers for Sewing-Machines, of which the following description, taken in connection with the drawings here-with accompanying, is a specification.

10 My invention relates to that class of sewing machines employing a rotary or oscillating looper for carrying the needle-thread loop around a bobbin to interlock with the under or bobbin thread. In machines of this 15 class it is customary to provide a means of some character for acting upon the bobbin-thread to draw off a sufficient length of the same from the bobbin as may be required for each stitch, and it has been the object of my 20 present invention to provide a simple and effective means for so acting on the bobbin-thread and which preferably will be capable of adjustment for regulating the amount of thread drawn from the bobbin according to 25 the thickness of the material being operated upon or the character of the work being performed.

To this end the invention consists in the novel features of construction and combinations of parts as hereinafter set forth in detail and pointed out in the claims.

Referring to the accompanying drawings, Figure 1, is a perspective end view of a machine embodying my invention, certain of 35 the parts located beneath the bed-plate being shown in dotted lines. Fig. 2, is a side elevation of the front end of the machine, with the bed-plate, shuttle, and shuttle-casement in section to more clearly show the several 40 parts, and also the action of the same upon the thread at a certain time during the formation of a stitch. Fig. 3, is a bottom view of the front end of the machine, with the shuttle and shuttle-casement removed. Figs. 45 4 and 5 are enlarged detail views showing the position of certain parts of the thread controller mechanism at different times during the operation of the machine.

To explain in detail, the head a of the machine, the rotary shuttle or looper a^2 , the bobbin-holder a^3 , the rotating driving shaft a^4 , the shuttle-driver a^5 , the presser a^6 , the needle a^7 , the take-up a^8 and the tension-device a^9 , are all of the usual and well 55 known construction as found in the "Stand-

ard" sewing machine, to which, as herein illustrated, I have applied my invention.

According to my invention, I have provided a thread-controller, consisting of a sliding bar b which is supported to operate 60 on the under side of the bed-plate of the machine, with one end thereof arranged to reciprocate across the path of the needle in a position immediately beneath the throat-plate and between the latter and the shuttle 65 with its contained bobbin-case and bobbin, which end is provided with an elongated slot or opening b' therein through which the thread is passed as will hereinafter be described. The said slotted end of the bar b , 70 as herein shown, rests upon the upper surface of the shuttle-race frame c within a groove c' therein as shown by dotted lines in Fig. 1, within which groove the said slotted or thread-engaging end of the bar b is supported and guided. The rear or opposite 75 end of the bar b has a hinged connection with a pivoted lever d , which latter, as herein shown, is arranged at substantially right angles to the driving shaft a^4 and is pivotally secured at one end to the under side of the bed-plate at d' . This lever d is provided with a stud having an anti-friction roller d^2 thereon which is adapted to be engaged by a cam e located upon the driving-shaft a^4 , from which the lever d is caused to receive a vibrating movement and thereby 80 give the connected thread-controller bar b a longitudinal reciprocating movement.

The bar b is movably held in a normal position with the slot b' therein in the path of the needle as shown in Figs. 1 and 3, by means of a fixed stud b^3 secured on the under side of the bed-plate, against which one end of the lever d is yieldingly held by a spring d^3 . 90 The latter is supported upon a post d^4 with one end thereof bearing against the lever d as shown. By this arrangement of parts, the bar b is moved positively in one direction by the cam e when drawing the thread 95 from the bobbin as will be described, and is returned to its normal position by the spring d^3 .

The operation or action of the controller b relative to the movements of the co-acting 100 parts of the stitching mechanism, is as follows: In taking the first stitch, (it being understood that the controller b is in the position shown in Figs. 1 and 3) to allow for the passage of the needle through the open- 105

ing therein) the needle passes downward through the opening b' in the controller b , and, when the needle-thread loop has been carried around the bobbin by the shuttle and drawn up by the take-up in the usual manner, it also carries the bobbin-thread up through the said slot in the controller. After the bobbin-thread, represented at 2, has been thus passed upward through the opening in the controller b , and through the needle-opening f in the throat-plate; at each succeeding stitch, the needle descends through said openings into the proper position relative to the shuttle to have the needle-thread loop engaged by the latter in the usual manner.

The movement of the controller b is so timed by the cam e , that it remains stationary during the downward movement of the needle and until the latter has been raised well above the same, during which time the needle-thread loop, represented at l , has been carried around the bobbin by the shuttle to a position as shown in Fig. 1, where it is cast off by the latter to be drawn up by the take-up, at which time, the controller b begins to be moved backward by the cam e , as shown in Fig. 2, (which view shows the controller in a position at the limit of its backward movement) and draw a certain regulated amount of thread from the bobbin, it being understood that during such movement of the controller to draw the bobbin-thread off the bobbin, the needle-thread is in a slack condition and being drawn up by the take-up, and consequently is not affected by the action of the controller. After the controller has drawn off the desired amount of thread from the bobbin, it is then returned to its normal position under the action of the spring d^3 before the take-up has reached the limit of its upward movement, so as to present the bobbin-thread in a slack condition to the upper thread and allow it to be drawn into the goods by said upper thread without undue strain on the same as will be readily understood.

The movement of the controller b may be regulated to draw off more or less thread from the bobbin, according to the thickness of the material being operated upon or the character of the work being performed, by adjusting the position of the cam e longitudinally upon the shaft a^4 , by means of a set-screw e' , whereby said cam will be caused to move the lever d and thereby the connected controller b a greater or less distance. The necessary length of under or bobbin thread required for any desired length or character of stitch being thus drawn from the bobbin and given in a slack condition to the upper thread, so that it may be drawn through the goods by the latter when acted upon by the take-up, without any undue strain on said upper thread, enables the operator to per-

form varied kinds of work upon goods of different kinds and thicknesses with the best results, and is especially desirable in buttonholing when the operator wishes to adjust the stitch for making different widths of 70

which the cam is regulated to secure. Such a grooved cam, forming a positive means for regulating the movement of the roller, has been found to be desirable when the 5 machine is run at a high rate of speed, as otherwise the tension of the spring b^3 is liable to be overcome sufficiently by the sudden contact of the ordinary face-cam with the roller d^2 , as to allow the thread-controller 10 to be thrown beyond the required regulated distance. Such excess movement however is prevented by the grooved cam as described.

Having thus set forth one practical embodiment of my invention, I do not wish to 15 be understood as being confined to the particular form or arrangement of the controller b , or the particular construction or arrangement of the means for operating said controller, or the particular character of the 20 stitching mechanism as herein illustrated and described, as it will be obvious that the same may be more or less materially modified without departure from the spirit of my invention, for

25 What I claim as new and desire to secure by Letters Patent of the United States is,

1. In a sewing machine, the combination, with the needle, a bobbin, and a looper, of a bobbin-thread controller having means for 30 engaging the bobbin-thread, means movably holding said controller in a normal stationary position, means, independent of said holding means, for operating the controller positively to draw the thread from the bobbin, and means for adjusting the throw of 35 said controller, for the purpose set forth.

2. In a sewing machine, the combination,

with the needle, a bobbin, and a looper, of a reciprocating bobbin-thread controller having means for engaging the bobbin-thread, means movably holding said controller in a normal stationary position, 40 means, independent of said holding means, for operating the controller positively to draw the thread from the bobbin, and means 45 for adjusting the throw of said controller, for the purpose set forth.

3. In a sewing machine, the combination, with the needle, a bobbin, and a looper, of a bobbin-thread controller having means for 50 engaging the bobbin-thread, means movably holding said controller in a normal stationary position, and a rotating shaft having a cam thereon for operating the controller to draw the thread from the bobbin, said cam 55 being adjustable on its shaft, for the purpose set forth.

4. In a sewing machine, the combination, with the needle, a bobbin, and a looper, of a reciprocating bobbin-thread controller 60 having means for engaging the bobbin-thread, a lever connecting with said controller, means movably holding said lever and connected controller in a normal stationary position, and a rotating shaft having 65 a cam thereon for operating said lever and connected controller to draw the thread from the bobbin, said cam being adjustable on its shaft, for the purpose set forth.

DANL. MILLS.
